UNITED STATES PATENT OFFICE.

HENRY A. FRAMBURG, OF BERWYN, ILLINOIS, ASSIGNOR TO H. A. FRAMBURG & COMPANY, OF CHICAGO, ILLINOIS, A CORPORATION OF ILLINOIS.

ILLUMINATING-FIXTURE.

1,197,812.

Specification of Letters Patent. Patented Sept. 12, 1916.

Application filed April 21, 1916. Serial No. 92,631.

To all whom it may concern:

Be it known that I, HENRY A. FRAMBURG, a citizen of the United States, residing at Berwyn, in the county of Cook and State of Illinois, have invented a certain new and useful Improvement in Illuminating-Fixtures, of which the following is a full, clear, concise, and exact description, reference being had to the accompanying drawings, 10 forming a part of this specification.

My invention relates to illuminating fixtures, more particularly of the concealed type for illuminating fixed areas, such as bank windows, show cases, display windows 15 and the like.

Heretofore devices of this class have not been wholly satisfactory due to the fact that such devices are required to be placed in a corner or against the wall or a window and 20 being so placed are rendered inaccessible for cleaning and for lamp renewals which must be performed frequently to obtain satisfactory operation. It is usual to provide a translucent or transparent panel in the bottom of the device and due to the requirement 25 for cleaning both sides of the panel, the same is usually hinged to the remainder of the fixture. If the panel is hinged at the front, that is, adjacent the wall where the 30 fixture is mounted, the panel upon being released, will swing down and may break or may mar or crack the wall or glass. If it is hung on the rear edge of the device, this hinged panel is in the way of cleaning and 35 renewals, and in addition it is difficult to fasten up in place.

My invention aims to provide an improved structure which will remove the above difficulties and which will permit of ready and 40 convenient cleaning of the device of both sides of the panel and will permit lamp renewals to be readily performed and which will be relatively simple and inexpensive.

In the accompanying drawings I have 45 illustrated one embodiment of my invention.

Figure 1 is a perspective view showing one panel in open position; Fig. 2 is a sectional view taken on the line 2-2 of Fig. 1; Fig. 3 is a plan bottom view of the device 50 showing one door moved to the open position; Fig. 4 is a cross sectional view taken on the line 4-4 of Fig. 2, showing the glass panel in closed position; Fig. 5 is a similar view showing the panel moved out edgewise

to the limit of such movement; Fig. 6 is a cross sectional view taken on the line 6-6 of Fig. 2 showing the glass panel of that side dropped down into normal open position; Fig. 7 is a diagrammatic view illustrating the manner of applying the fixture 60 to a bank cashier's window; and Fig. 8 is a fragmentary detail view.

In the figures a two light unit has been illustrated.

The device comprises a hollow casing having the front wall 10 and a top wall 11 which are, in this embodiment, secured to each other substantially at right angles. A rear curved wall 12 joins by means of a short vertical section 13 the top wall 11 so as to 70 form a channel 14 in the top of the casing. Suitable end walls 15 and 16 close the end of the casing. The bottom of the casing is provided with two pairs of guides 17, 18 and 19, 20 for supporting the translucent 75 or transparent panels 21 and 22 respectively.

The panels 21 and 22 preferably consist of a central portion of frosted glass surrounded by and mounted in suitable metal frames 23 and 24 respectively. A rim 25 80 turned inwardly from the bottom wall covers the front edge of the panel frames 23 and 24 as shown at the right in Fig. 3.

The channel 14 is preferably closed by a channel bar 26 which incloses the electrical 85 conductors 27 for supplying the lamps 28 and 29. The lamps 28 and 29 are supported by suitable brackets 30 and 31 secured at their upper ends to the channel bar 26.

It can be seen that this type of device is 90 adapted to be mounted in the corner of the wall or cage as shown in Fig. 7, against the frame 32 of the cashier's window which is provided with a transparent portion 33. The transparent portion 33 may be opened 95 or may be replaced by suitable bars or fixtures. It can be seen at once that the shelves or tables 34 and 35 will be properly illuminated. If desired, the interior of the rear wall 12 may be provided with suitable reflecting surface or may itself form the reflector. 100

If the panels 21 and 22 were hung at the front of the device, it is obvious that when the same were swung downward they would 105 strike against the window 33 and would either demolish themselves or mar this window. If these panels were hinged at the rear

it is obvious that it would be difficult to fasten them in closed position. According to my invention these panels are opened by means of a compound movement so that 5 they are in effect hung or hinged to the rear portion, but are also fastened at that point when in the closed position.

The edge of the panel frame lying adjacent the front wall 10 when the panel is in 10 the closed position is provided with a wire stiffening and pivot member 36, which is slightly longer than the main frame of the panel so that it projects a short distance at each end and prevents the panel from being 15 withdrawn sidewise as shown in Fig. 3. The rear curved wall 12 is provided with the flange portions 37 and 38 which catch the pivot member 36 and prevent the slide from being withdrawn laterally. The frame of 20 the slide or panel is notched, as shown at 39 and 40, in order to permit the panel to swing downwardly into the position shown in Fig. 1, these notches providing clearance for the ends of the guides 17, 18 and 19, 20 when 25 the slide is swung downward. The guides 17, 18 and 19, 20 are provided adjacent the rear end of the device, as shown in Figs. 4, 3, and 6, with stops or projections 41, which lie in the path of the ends of the pivot member 36 which project beyond the slide so 30 that when the slide is folded down into the position shown in Figs. 1 and 6, it will be impossible to move the slide laterally since the projection 41 at each end engages the adjacent end of the pivot member 36. However, when the slide is raised to the position 35 shown in Fig. 5, the pivot member 36 will rise over the stop 41 and will permit the slide to be moved into place edgewise. At 40 the end walls 15 and 16 suitable guides 42 are arranged to receive the pivot member 36 and to hold the adjacent portion of the panel firmly against the slide and thus prevent rattling or misplacing of the slide. As 45 shown in Fig. 2, the guides or ways 18 and 19 are formed of strips of sheet metal bent into angle bars and the ends of these bars are bent downward to form the guides 42. The free edge of each slide is provided with 50 setscrews 44 which, when the slides are in place, register with suitable holes 45 in a flange 46 formed on the rear wall 12, as shown at the right of Fig. 1. The set screws 44 may be merely drawn tight against the flange 46, if desired, or any other suitable 55 fastening means may be provided.

The operation of the device is as follows: The casing is positioned preferably in a corner or at a cornice in the manner shown in 60 Fig. 7 so that the light from the electric lamps 28 and 29 will be cast downward upon the area to be illuminated. When it is desired to open the casing, the set screws 44 are released and the slide is drawn out edgewise, as is shown in Fig. 5, until the pivot

member 36 stops further movement. The outer end of the slide is then dropped downward, as shown in Figs. 1 and 6, the notches 39 and 40 clearing at this time the edges of the guides 19 and 20. The pivot member 36 70 lies between the front flanges 37 and 38 upon the front, and the stop 41 on the rear so that the slide cannot be moved backward or forward but will remain in this position while cleaning or lamp renewal is being carried 75 on. When it is desired to close the slide, the outer end is raised into the position shown in Fig. 5 and the slide is pushed edgewise into place. The pivot member 36 rides over the stop 41 and slides backward until it is 80 guided between the guides 42 and the guides 17, 18 or 19, 20 as the case may be. The stops 41 do not interfere with the movement of the panel itself inasmuch as the frame of the panel is narrower than is the pivot member 85 36 as shown in Fig. 8. When the panel has been pushed to the proper position the set screws 44 are tightened to project into the holes 45 so that the slide cannot be moved edgewise and as a consequence the 90 slide or panel will be locked into position.

I do not intend to be limited to the precise form or proportions shown and described, as the invention may appear in other mechanisms than the one I have illustrated.

It is apparent that the device may be secured or suspended from above. If desired the two sides of the casing may be made symmetrical. I employ the term translucent to mean capable of transmitting light to 100 distinguish from the term opaque.

I claim:

1. In combination a casing having an open bottom portion, lamp supporting means in said casing, a movable bottom containing a 105 translucent portion, horizontal guides for said bottom, pivot means on said bottom for preventing complete withdrawal of said bottom from said guides, said bottom being adapted to be swung about said pivot after the same is moved to the outermost position on said guides and means for holding said bottom on said guides in position to close said opening.

2. In combination a casing having an open bottom portion, lamp supporting means in said casing, a movable slide having a translucent portion, said slide being adapted to close the bottom of said casing, horizontal guide means on said casing to support said slide, pivot means on one edge of said slide, means on said casing to engage said pivot means to prevent withdrawal of said slide from said casing, said slide being adapted to be rotated about said pivot means when the same engages said means on the casing, and holding means for preventing said slide in closed position from being moved horizontally on said guide.

3. In combination, a casing, lamp sup-

- porting means in said casing, a movable slide having a translucent portion, guide means on said casing to support said slide, pivot means on one edge of said slide, said slide having a notch adjacent said pivot means to permit said slide to be swung about said pivot means and stop means on said casing to prevent a motion of translation of said slide when said slide has been drawn outward on said guide and rotated.

4. In combination, an open casing, lamp supporting means in said casing, a slide for closing said casing, said slide having a transparent portion, guiding means on said casing for supporting said slide in position to close said opening, a pivot member projecting from each side of said slide, said casing having means to engage said pivot member to prevent withdrawal of the same from said guiding means, said slide being adapted to swing about said pivot member from its horizontal position and means for preventing movement of said slide sidewise when it is swung about the pivot.

5. In combination, an open casing, lamp supporting means in said casing, a movable slide for closing said opening, said slide having a translucent portion, guide means on said casing to support said slide in position to close said opening, pivot means on one edge of said slide for pivotally supporting the slide when in open position, means on said casing to engage said pivot means to prevent withdrawal of said slide means for holding said slide firmly in position on said guides to close said casing and means to prevent lateral displacement of said slide when the same is swung about said pivot means.

6. In combination an open casing, a slide member having a transparent portion, guiding means along the open side of said casing for supporting said slide in position to close said opening, a pivot member projecting from each side of said slide, said casing having means at one end of said guiding means to engage said pivot member to prevent its being withdrawn completely from said casing and means at the other end of said guiding means for engaging the pivot member when the slide member is in position to close said open casing for preventing upward movement of the inner end of said slide.

7. In combination an open casing, a slide having a translucent portion for closing said opening, guiding means on said casing for supporting said slide, a pivot member projecting from each side of said slide, said casing having means to engage said pivot member to prevent its being withdrawn completely from said casing, said casing having stop means at one end of the guiding means to prevent movement of said pivot member out of the guiding means and having further means at the other end of said guiding

means for engaging said pivot member to hold the inner end of said slide against upward movement.

8. In combination a casing having an open bottom, guide members along the sides of said opening, a slide movable in said guide members, said slide being normally held in said guide to close said opening, pivot means on one end of said slide, said slide being movable out of said guide, means on said casing for engaging said pivot means, said slide having notches adjacent said pivot means to permit the slide to be swung about the pivot means, said notches preventing more than a predetermined amount of motion of said slide with respect to said guide when said slide is swung about the pivot means.

9. In combination a casing having an open bottom, guide members along the sides of said opening, a slide movable in said guide members, said slide being normally held in said guide members to close said opening, pivot means on one end of said slide, said slide being movable out of said guide members, means on said casing for engaging said pivot means, said slide having notches adjacent said pivot means to permit the slide to be swung about the pivot means, said notches preventing more than a predetermined amount of motion of said slide with respect to said guide members when said slide is swung about the pivot means, and means for preventing a motion of translation of said slide when the same is swung about said pivot.

10. A casing having an open bottom, a slide for closing said open bottom, said casing having lateral flanges extending inward so that the space between said flanges is less than the width of said slide, said flanges serving as guides to hold the slide in position to close the opening, pivot members extending from the sides of said slide at the back edge thereof, said slide having notches in the side edges in front of said pivot members, means on said casing to prevent said pivot members being withdrawn from said flanges, and means on the rear end of said flanges to engage said pivot members when said slide is in the closed position for preventing the rear end of said slide from moving upwardly.

11. A casing having an open bottom, a slide for closing said open bottom, said casing having lateral flanges extending inward so that the space between said flanges is less than the width of said slide, said flanges serving as guides to hold the slide in position to close the opening, pivot members extending from the sides of said slide at the back edge thereof, said slide having notches in the side edges in front of said pivot members, means on said casing to prevent said pivot members being withdrawn from said flanges, and means on the rear end of said flanges to engage said pivot members when said slide is in the closed position for preventing the rear end of said slide from moving upwardly.

withdrawn from said flanges, and means on the rear end of said flanges to engage said pivot members when said slide is in the closed position for preventing the rear end of said slide from moving upwardly and stop means to prevent said slide being moved inwardly when it is swung out of the plane in which it normally lies when closing said opening.

10 12. In combination a generally prismatic casing adapted to be placed in the corner between a horizontal wall and a vertical wall, said casing having an open bottom, a translucent slide for closing said opening,

said casing having horizontal guide means 15 along the bottom to hold said slide, pivot means on one end of said slide and fastening means for the other end of said slide to permit said slide to be slid out edgewise and then swung about the edge of the opening remote from both of said walls, the fastening means for the slide being adapted to coöperate with the same edge of the casing to hold said slide in closed position.

20 In witness whereof, I hereunto subscribe 25 my name this 7th day of April, A. D. 1916.

HENRY A. FRAMBURG.
